Primary Examiner — Garth Rademaker*Assistant Examiner* — Benjamin D. Wannemacher(74) *Attorney, Agent, or Firm* — QuickPatents; Kevin Prince(57) **CLAIM**

The ornamental design for a ladder wall bracket, as shown and described.

DESCRIPTION

FIG. 1 is a front perspective view of a ladder wall bracket, showing my new design;

FIG. 2 is an enlarged front perspective view thereof;

FIG. 3 is a front elevational view of FIG. 2;

FIG. 4 is a rear elevational view of FIG. 2;

FIG. 5 is a left-side elevational view of FIG. 2;

FIG. 6 is a right-side elevational view of FIG. 2;

FIG. 7 is a top plan view of FIG. 2; and,

FIG. 8 is a bottom plan view of FIG. 2.

The broken lines in FIG. 1 showing a ladder depict environmental matter that forms no part of the claimed design. The dot-dash broken line in the drawings represents a boundary of the claimed design. The remaining broken lines in the figures depict portions of the ladder wall bracket that form no part of the claimed design.
